SCREEN

Rolland M. Stowe, Corry, Pa., assignor to Corry Metal Corporation, Corry, Pa., a corporation of New York

Application April 2, 1937, Serial No. 134,612

7 Claims. (Cl. 156—14)

This invention relates to an improvement in screens for windows and more particularly windows of the casement type.

Except for the projecting hardware, the inner face of a casement window structure is entirely suitable for positioning an inside screen. Inasmuch as operators and latching devices are generally manually controlled, levers or handles must project inwardly of either frame or window. Thus, a standard screen would not be adapted for use on windows of this type. It has been attempted to overcome screening difficulties by providing one or more suitable openings in the screen cloth and projecting the hardware therethrough.

Another effort in this direction has been to locate the latching and operating devices somewhat away from the inner edge of the frame for the purpose of leaving a small surface against which the rail of a screen might abut. In the first instance mentioned it is difficult to entirely eliminate a constant opening in the cloth, and thus the purpose of the screen is somewhat defeated. In the second instance, special hardware is required, necessitating more costly installation.

The present invention is directed to the provision of a screen, inexpensive to manufacture, which does not require the use of special hardware and takes substantially the form of a standard screen. The rails of the screen at one or more points may be bowed or arched to provide a recess or compartment adjacent the casement and into which any projecting portions of operating, latching or hinge hardware may locate. Provision of these recesses allows all other parts of the screen rails to abut the frame and prevents ingress of insects.

The principal object of the invention lies in the provision of a screen adapted for use with windows of a casement type.

Another object of the invention lies in the provision of a screen having a portion of the rail laterally offset to clear projections on casement hardware.

Another object of the invention lies in the provision of a screen having one or more portions of the rail laterally arched or bowed to create a recess into which surface hardware of the frame or window may project.

Another object of the invention lies in the provision of a screen having adjustable hinge connection with the frame whereby the screen, during the process of installation, may be laterally adjusted to locate the casement hardware within the recess or recesses formed in the screen rails in accordance with the invention.

Other and further objects of the invention will be more fully understood from a consideration of the following specification taken in conjunction with the accompanying drawings and in which

Fig. 1 is a front elevation of an outwardly swinging casement window provided with a screen in accordance with one form of the invention;

Fig. 2 is an enlarged fragmentary elevational view of that portion of the screen structure adjacent the window latch shown in Fig. 1;

Fig. 3 is a horizontal sectional view taken substantially on the line 3—3 of Fig. 2;

Fig. 4 is a vertical edge view of a portion of the screen rail;

Fig. 5 is a view taken substantially on the line 5—5 of Fig. 4;

Fig. 6 is a horizontal sectional view taken substantially on the line 6—6 of Fig. 2;

Fig. 7 is an end view of the keeper for the casement and screen latches, being taken substantially on the line 7—7 of Fig. 2;

Fig. 8 is a perspective view of a modification of the screen shown in Fig. 1;

Fig. 9 is an enlarged fragmentary vertical sectional view showing the screen of Fig. 8 applied to a bottom pivoted window; and

Fig. 10 is a horizontal sectional view, taken substantially on the line 10—10 of Fig. 9.

Reference is now had to the drawings wherein the reference numeral 10 generally indicates a casement window fitted with a screen. The window 10 includes a casement frame 11 of any suitable cross sectional design. This frame includes inner flanges 12 and 13 connected by a web 14. The sash 15 may be of any suitable cross sectional design and comprises an inner flange 16 connected with an outer flange 17 through a web 18. Referring to Figure 3 of the drawings, it will be noted that when the window is closed, flange 16 abuts flange 12 and flange 17 abuts flange 13. Located on the vertical rail adjacent the free edge of the window 15 is a plate 20. The plate 20 may be secured along a flange 21 thereof to flange 16 in any suitable manner, as by screws 22. Mounted on the plate 20 is a latch 23 which comprises a central portion 24 through which a bolt 25 projects into the plate 20, being secured for pivotal movement by a nut 26. The latch includes an operating handle 28 and a bolt 30. The bolt 30 projects a convenient distance beyond one vertical edge of the frame flange 12 and is movable about the bolt 25 by manipulation of the handle 28.

Secured to the flange 12 in any suitable man-

ner, as by screws 32, is a keeper 33. This keeper is formed with a cam-like surface 35 which terminates in a ledge 36. Above the ledge 36 the keeper is formed with a rolled or bead-like portion 37, the upper end 38 of which is slightly spaced from the flange 12 to provide an opening 39.

A screen generally indicated by the numeral 41 is adapted to be positioned against the inner face 10 of the casement window above described. This screen is rectangular in shape and includes rails 42. Each rail is formed with the usual recess 43 into which the edges of the wire cloth 44 project and are anchored by bars or bead-like members 15 45. It will be noted that in the present illustration of the invention the latch member 23 is midway of the free rail of the window 15, and the bolt 30 thereof, as well as the keeper 33, projects inwardly of the frame flange 12 one-half inch or 20 more. The screen is adapted to be so mounted that the outer faces of the rails 42 abut the inner faces of flanges 12 of the casement frame. It is evident, however, that, since the bolt 30 and keeper 33 are located inwardly of the flange 12, 25 some provision must be made therefore. During construction of the screen frame, one of the vertical rails 42 thereof is laterally bowed or arched to provide an inwardly directed portion 47 in the rail. Secured to the vertical edge 48 of the portion 47 is a plate 50. This plate conforms generally to the contour of the portion 47 and provides therewith a pocket or recess 51 of a sufficient depth to accommodate the inwardly projecting bolt 30 and keeper 33. The plate 50 may 30 be formed with a rolled flange 52 which is adapted to mount a ring 53 usable in the process of opening and closing the screen. Within the recess 51 is an angle plate 55. This plate is secured in any suitable manner, as by a screw 56, against the inner face of plate 50. The flange 57 of the plate 55 is located adjacent the free edge of plate 50 and is adapted to substantially contact the flange 12 of the casement frame when the screen is in closed position.

45 One of the vertical rails 42 of the screen is provided with a pair of hinges 60. A hinge plate formed integral with or secured within the rail 42 terminates exteriorly of the rail in a portion 61. A right angle hinge plate 63 is provided with 50 interfitting rolled portions and a suitable pin 64 secures these elements together. The flange 65 of the plate 63 is provided with an open ended slot 66 through which a screw 67 projects into a drilled and tapped opening in the flange 12 of 55 the casement frame. Because of the slots 66 the screen may be adjusted laterally or may be slightly cocked one way or the other in the event that the recess 51, formed in the opposite vertical rail 42 of the screen, may fit over and enclose 60 the projecting portions of the window latch.

When the screen has been mounted and adjusted to enclose the latch, screws 67 are turned down to prevent displacement of the screen. For 65 purposes of explanation it is assumed that a screen is in closed position with the rails 42 in abutment with the flanges 12 of the casement frame. In this position the lower edge of the flange 57 of angle plate 55 will be located in the opening 39 which is between the bead 37 and casement flange 12 (see Figure 7). The screen is thus latched in closed position. When it is desired to open the screen, the operator grasps ring 53 and lifts upwardly to withdraw flange 57 from out of the opening 39 and beyond the edge of the bead 70 75 37. It will be understood that vertical movement

of the free edge of the screen to clear the bead 37 is provided in either of two ways. The hinges 60 may be provided with a slight play or looseness which will facilitate moving the entire screen upwardly to clear the bead, or the entire screen 5 may be slightly distorted out of its true shape. In the first instance the weight of the screen will normally hold the flange 57 in place in the opening 39, and in the second instance, the 10 springiness of the screen frame will serve this purpose. It is, therefore, possible to entirely eliminate a screen spring latch of any kind. When it is desired to close the screen, the operator lifts slightly on the ring 53 and flange 57 moves over bead 37 into the opening 39.

15 Examination of Figures 2 and 3 discloses the handle portion 28 of the latch 23 to project outwardly of the vertical plane of the casement frame 11. Accommodation for this projecting portion of the latch is automatically provided for. Since 20 the screen rail 42 is arched or bowed outwardly, the wire cloth 44 at this point must also be arched or bowed. It is thus evident that the wire cloth forms a recess into which any portion of the handle 28 may project without contacting said cloth. 25

Reference is now had to the modification of the drawings shown in Figures 8 to 10. In this modification a casement window generally indicated by the reference numeral 70 is shown. The window is of the type frequently used in basements and swings inwardly rather than outwardly as in the case of the structure heretofore described. The casement frame 71 includes an inner flange 72, web 73, and outer flange 74. The window 75 includes a frame having an inner flange 77, web 78, and outer flange 79. As shown in Figure 9 of the drawings, the window flange 79 abuts the outer face of flange 74. This arrangement is only along the lower rail of the window structure, the side and top rails being arranged in reverse position substantially as shown in Figure 10. The purpose of this is to make possible swinging the window inwardly as shown in dotted line of Figure 9. It will be noted that as the window is moved inwardly, the frame flange 79 45 thereof swings outwardly. A screen having rails positioned against the outer face of flange 74 of the casement frame would interfere with the outward and upward movement of flange 79 of the window when the window is moved to open position. To make possible the use of a screen with a casement window of this type it is contemplated to provide a screen of the type generally indicated by the reference numeral 80. The screen includes rails 81 which are formed with recesses 82 into 55 which a bead-like member 83 projects to anchor wire cloth 84. The side rails of the screen adjacent their lower ends are projected outwardly and thence downwardly. The purpose of this is to provide a pocket or recess 86 between the frame 60 71 and the lower portion of the screen. A gap at the bottom of the screen is thus produced which is closed by a plate 87. This plate is secured in any suitable manner, as by welding, to the lower rail of the screen and projects horizontally inwardly to contact the flange 74 of the lower rail of the casement frame. Two further plates 88 are provided. These plates are secured to the edges 65 of the side rails in any suitable manner as by welding, and serve to enclose the ends of the recess 86. Plates 88 may be formed integral with plate 87 and be bent upwardly along the edges of the side rails as found most convenient.

70 75 It will be noted that when the screen 80 is positioned with respect to the window 70 and so 75

held by spring pins 89, that the side and top rails abut flanges 14 of the casement frame and that the bottom rail is somewhat removed from the bottom flange 14 of the casement frame. Thus when the window is swung inwardly, flange 19 thereof is free to move within the recess 86. It is impossible for insects to enter around the screen since plates 87 and 88 contact the casement frame at all points where the screen rails do not so contact.

Although applicant has shown and described only two modifications of his invention, it will be apparent to those skilled in the art that other modifications or adaptations of the invention are contemplated in so far as these modifications are within the spirit and scope of the invention as defined by the hereunto annexed claims.

Having thus set forth my invention what I claim as new and for which I desire protection by Letters Patent is:—

1. A screen, applicable to the frame of a casement window, comprising rails forming a rectangular frame, wire cloth extending across said frame, means securing said cloth to said frame, a portion of said screen frame being bent inwardly away from said window to provide a depression in one face thereof, a plate secured to said portion and forming therewith a recess into which projecting portions of hardware of said window may project whereby to facilitate abutment of all other parts of said screen frame with the frame of the casement window.

2. A screen, applicable to the frame of a casement window having a keeper, said screen comprising rails forming a rectangular frame, wire cloth extending across said frame, means securing said cloth to said frame, a laterally arched portion in said screen frame, means cooperating with said portion to form a recess for receiving any projecting portions of the hardware of said window, a latch plate in said recess, said latch plate being engageable with said keeper to secure the frame of said screen in abutment with the frame of said window.

3. A screen, applicable to the frame of a casement window, having an inside window latch and keeper, said screen comprising rails forming a rectangular frame, wire cloth extending across said frame, means securing said cloth to said frame, a laterally arched portion in one of the rails of said frame, a plate joined to said portion and forming a recess therewith, a latch plate in said recess, hinge means mounting said screen on the frame of said window, said screen being movable to enclose said window latch within said recess and facilitate abutment of the rails of said frame and said plate with the frame of said window, said latch plate being engageable with said keeper to secure said screen in closed position.

4. A screen, applicable to the frame of a casement window having a window latch and keeper

positioned inwardly of the frame, comprising rails forming a frame, wire cloth extending across and secured to said frame, an inwardly arched portion in one of the rails of said frame, a plate joined to said portion and cooperating therewith to form a recess in which to receive said inwardly positioned window latch and keeper, and means on said plate engageable with said keeper to secure said screen in abutment with the frame of said casement.

5. A screen, applicable to the frame of a casement window having a window latch and keeper positioned inwardly of the frame, comprising rails forming a frame, wire cloth extending across said frame, a portion of one rail of said frame and the adjacent wire cloth being curved inwardly to provide a recess and being out of contact with said casement frame when said screen is in closed position, the curved rail and screen portion being positioned to receive said inwardly positioned window latch and keeper, and a plate joined to the inwardly curved portion of said rail, said plate serving to close the gap in said rail occasioned by said curved portion and partly closing said recess to prevent ingress of insects.

6. A screen, applicable to the frame of a casement window having a window latch and keeper positioned inwardly of the frame, comprising rails forming a frame, wire cloth extending across said frame, a curved portion in one of the rails of said frame, said curved portion being directed away from and out of the line of contact with the frame of said casement when said screen is in closed position, said rail portion being so located as to receive the inwardly positioned window latch and keeper, and a plate conforming to the shape of said recess, said plate being secured to the edge of said screen rail to partly close said recess and cooperating with the straight portion of said rail to provide full rail length engagement with the frame of said casement window when said screen is in closed position.

7. A screen, applicable to the frame of a casement window having window hardware, including a keeper, comprising a screen covered frame formed from a plurality of rails, the rails of said frame being adapted to abut the frame of said casement window when said screen is in closed position, a curved portion in one of the rails of said frame, said curved portion being directed away from and at all times out of contact with the frame of said casement window, said curved portion creating an opening adjacent the frame of said casement window, and a plate conforming generally to the contour of said recess secured to said curved portion, said plate serving to close the opening adjacent the frame of the casement window and cooperating with said rail to provide continuous contact of said screen with the frame of said casement window when said screen is in closed position.

ROLLAND M. STOWE.
